1.9 : Bottom

The design relates to a data processing device with two displays as illustrated by the following figures:

Figure 1 is a left view of a data processing device. Figure 2 is a front view of the data processing device. Figure 3 is a right view of the data processing device. Figure 4 is a rear view of the data processing device. Figure 5 is a perspective view of the data processing device. Figure 6 is a perspective view of the data processing device. Figure 7 is a perspective view of the data processing device. Figure 8 is a top view of the data processing device. Figure 9 is a bottom view of the data processing device.
